DISINFECTION MEANS

Wilhelm Neugebauer, Wiesbaden-Biebrich, Germany, assignor, by mesne assignments, to Alba Pharmaceutical Company, Inc., New York, N. Y., a corporation of New York

No Drawing. Application May 2, 1936, Serial No. 77,545. In Germany May 2, 1935

5 Claims. (Cl. 167—22)

The present invention relates to means for disinfecting.

It has been discovered that higher molecular sulphonium compounds, particularly compounds of this kind which contain one or more higher aliphatic or cyclo aliphatic, respectively, residues linked to the sulphur, can be employed with very great advantage as disinfecting means. The term "aliphatic" whenever used in the specification is, therefore, to be understood to include cyclo-aliphatic compounds. Sulphonium hydroxides and also the salts thereof may be employed. These compounds may, for example, be produced in the manner described in the French patent specification 773,254. One object of the invention is, therefore, a disinfecting and sterilizing agent which comprises a higher molecular sulphonium compound.

Compounds which contain higher molecular aliphatic or cycloaliphatic residues having more than six carbon atoms, such as dodecyl-, decyl- or hexadecyl residues, are particularly suitable. Residues which contain more than ten and less than twenty carbon atoms are most particularly suitable. The higher molecular residues may also be of an unsaturated nature. Moreover, they may carry substituents.

As suitable compounds there may be named by way of example: dodecyl-benzyl-methyl-sulphonium-methylsulphate, hexadecyl-ethyl-methyl-sulphonium - ethylsulphate, 2,6 - dichlorbenzyl - decyl-methyl-sulphonium-methylsulphate, oleyl-ethyl-methyl-sulphonium-bromide, [(diisobutyl) - phenyl] - benzyl-methyl-sulphonium-methylsulphate.

Salts of the following substances may also be used: o-chlorbenzyl-dodecyl-methyl-sulphonium-hydroxide, tetradecyl-dimethyl-sulphonium-hydroxide, α -naphththiomethyl-dodecyl-methyl-sulphonium-hydroxide, dodecyl-ethyl-methyl-sulphonium - hydroxide, didodecyl - methyl-sulphonium-hydroxide, abietinyl-dimethyl-sulphonium-hydroxide.

The compounds are characterized not only by possessing particularly high disinfecting properties but also by the fact that they only possess very slight poisoning action and that they are soluble in fats. Pathogenic bacteria, such as *Escherichia coli* and *typhus* bacteria, as also *staphylococci* are killed by highly diluted solutions of the sulphonium compounds.

The new compounds can be employed for the disinfection of the hands, for the disinfection of medical appliances and of skins, for the sterilization of adhesive substances and for all purposes for which other antiseptic or disinfecting means are customarily used. The disinfecting operation is preferably carried out by treating the objects to be disinfected for some time with dilute solutions of the sulphonium compounds. In this manner, for example, by means of a solution of dodecyl - dimethyl - sulphonium - methylsulphate (1:1000) *Escherichia coli* or *typhus* bacilli are killed within a few minutes. For killing *staphylococci* or *diphtheria* bacilli an aqueous solution of dodecyl - benzyl - methyl-sulphonium-methylsulphate (1:10000) may, for example, be employed.

I claim:

1. A disinfecting and sterilizing agent comprising a higher molecular sulphonium compound.
2. A disinfecting and sterilizing agent comprising a sulphonium compound containing an aliphatic residue having more than six carbon atoms.
3. A disinfecting and sterilizing agent comprising a sulphonium compound containing an aliphatic residue having more than ten and less than twenty carbon atoms.
4. A disinfecting and sterilizing agent comprising dodecyl-benzyl-methyl-sulphonium-methylsulfate.
5. A disinfecting and sterilizing agent comprising 2,6-dichlorbenzyl-decyl-methyl-sulphonium-methylsulfate.

WILHELM NEUGEBAUER.
